UNITED STATES PATENT OFFICE.

ROBERT E. YOLTON, OF BIRMINGHAM, ALABAMA, ASSIGNOR TO KILBY FROG & SWITCH COMPANY, OF BIRMINGHAM, ALABAMA, A CORPORATION OF ALABAMA.

SPRING HEAD-ROD FOR SPLIT SWITCHES.

1,285,545.

Specification of Letters Patent. Patented Nov. 19, 1918.

Application filed February 11, 1918. Serial No. 216,629.

To all whom it may concern:

Be it known that I, ROBERT E. YOLTON, a citizen of the United States of America, residing at Birmingham, in the county of 5 Jefferson and State of Alabama, have invented certain new and useful Improvements in Spring Head-Rods for Split Switches, of which the following is a specification.

10 My invention relates to an improvement in split switches and has for its object to provide a spring attachment for the head rod of the same which will allow the trains to trail through the switch without damage to 15 any of the parts of the switch.

More particularly the object of my invention is to design a spring head rod in which the spring is incased and protected from the deteriorating effects of the weather, and 20 which is neat, compact and composed of but few parts which are designed for easy assemblage and for durability in service. My invention is also adapted for attachment to the head rod of any split switch.

25 My invention further comprises the novel details of construction and arrangements of parts which are hereinafter more particularly described and pointed out in the claims, and which are illustrated in their 30 preferred embodiments only in the accompanying drawings which form a part of this specification, and in which:—

Figure 1 shows my improved head rod in plan view connected to the switch points.

35 Fig. 2 is a bottom view of the top casting, and

Fig. 3 is a plan view of the bottom casting, which castings together form the spring housing.

40 Fig. 4 is an enlarged longitudinal sectional view taken on the line 4—4 of Fig. 1.

Similar reference numerals refer to similar parts throughout the drawings.

I have illustrated my invention as applied to the switch points 1, 1, which are assembled with the track rails 2, 2, and are connected to the ordinary switch head rod 3. This head rod, as illustrated, carries at each end a forging 4 which is bolted to the web 45 5 of the adjacent switch point and which has a hold-down extension 6 which works under the adjacent track rail 2 and under the switch rail 1. Any other well known

50 type of split switch head rod may be employed as my invention consists essentially 55

in the spring attachment for connecting the switch throw rod 7 to the head rod 3.

In the embodiment of my invention illustrated, the throw rod has its yoked end 8 adapted to straddle and to be connected by 60

a bolt 9 to the end 10 of the casting 11 forming the top member of the spring holder. This casting 11 is provided at its center with a semi-cylindrical recess or chamber 12 and has semi-circular ends 13 each provided 65

with side webs 14 adjacent to the chamber 12 and with a depending end lug 15. The under faces of the webs 14 lie in the bottom plane of the casting. A transverse hole 16 is drilled or otherwise provided in each lug 70

15. The casting forming the bottom member 17 of the spring holder is shown in Fig. 3, and comprises a side flange 18 which is connected by bolts or rivets 19 to the center of the head rod 3. This casting has a semi- 75

cylindrical recess 20 corresponding in size and shape to the recess 12 in the top member 11 and has semi-circular ends 21 which are shorter than the ends 13 and each provided with a beveled end edge 22 having a 80

corresponding slope and length to the inner beveled edge 23 of the adjacent lug 15. A bottom segmental projection 24 at each end of the member 17 is shaped to fit under a lug 85

15 and to complement the same so that they 90 jointly form a circle. At each end of the recess 20 the casting 17 has a segmental spring centering lug 25 and in the bottom of this recess I provide drain holes 26. The recessed portion of the casting 17 is reinforced by external ribs 27 which extend to 95

and form shoulders which abut against the head rod 3. A coil spring 29 is adapted to be received in the circular chamber or housing formed by the recesses 12 and 20 in the 100 two castings 11 and 17 and it is centered therein by the lugs 25. The pipe sleeves 30 receive the adjacent ends of the portions 13 and 21 and are secured in place by bolts 31

passing through the holes 16 in the lugs 15. 105 The length of the sleeves is sufficient to engage and guide the adjacent shorter member 21 throughout its movements.

To assemble a spring head rod using my invention, three holes are drilled near the center of an ordinary head rod 3 to match the holes 28 in the flange 18 of the holder member 17 and this member is then bolted or riveted to the rod 3. A coil spring 29, which preferably should be three-fourths 110

of an inch longer than the recess 20, is compressed and inserted into the said recess 20 in which it is permitted to expand and engage the lugs 25. The top casting or holder member 11 is then placed over the member 17 with the top half of the spring entering the recess 12 therein. The pipe sleeves 30 are then slipped over the ends of the holder members 11 and 17 and bolted in place by the bolts 31. It will be noted that in normal position the ends 21 of the bottom holder member are each sufficiently shorter than the corresponding end 13 of the upper holder member to allow an endwise play, before the engagement of the faces 22 and 23, equal to the play required by the head rod to permit the train to trail through the switch without damage to any of the parts of the switch.

20. In operation, with the switch points standing as shown in Fig. 1, should a train trail through the switch the head rod 3 would be shifted to the left, carrying with it the spring holder 17 which would slide under the top member 17 to the left in the sleeve 30 and compress the spring 29, which would serve to return the head rod to its previous position as soon as the train had trailed through. A similar operation would obtain if the head rod 3 were shifted to the right.

The object of the webs or flanges 14 is to prevent the recess 20 in the lower member of the holder becoming uncovered when it moves out of register with the recess 12 in the top member. By this arrangement dirt and foreign matter are very largely prevented from gaining access to the spring chamber so that the spring itself is protected from the deteriorating effects of the weather. The engagement of the faces 22 and 23 on the holder members will serve to positively limit the extreme relative movement in either direction of the holder members.

This invention is not intended to be restricted in scope to the specific embodiment shown, but contemplates such modifications as come within the spirit and scope of the claims.

Having thus described my invention, what I claim as new and desire to secure by Letters Patent, is:—

55. 1. In a split switch head rod, a spring holder connected to the rod, a coiled spring mounted under compression in said holder with the upper longitudinal half thereof exposed, a cover slidably mounted on the holder and having seats which engage both exposed ends of said springs, and means to connect said cover to the switch operating mechanism.

60. 2. The combination with a split switch head rod and its throw rod, of a spring

connection for said rods, comprising two recessed spring housing members, means to hold said members assembled free for relative sliding movements, a spring in the recessed portions of said housing members 70 adapted to resist said sliding movements in either direction, and means connecting one member to the throw rod and the other member to the head rod, substantially as described.

75. 3. In combination, a head rod, a spring holder member connected thereto, a throw rod, a spring holder member connected thereto, guides to slidably connect said members, and a spring housed by said members and adapted to resist relative sliding movements between them in either direction, said housing members forming a chamber in which the spring is protected from the weather.

80. 4. A spring connection for the head rods of split switches, comprising one member adapted to be connected to the head rod, another member adapted to be connected to the switch throw rod, a spring housing formed in part by each of said superimposed members, means to hold said superimposed members in sliding engagement, and a coil spring in said housing disposed to resist relative movements in either direction between said housing members.

85. 5. The combination with a split switch head rod and its throw rod, of a spring connection between said rods comprising two castings, each having a longitudinal part of a common spring chamber formed therein and end extensions beyond the chambered portion of the upper casting, a coiled spring in said chamber, lengthwise guides which 90 slidably connect said castings for endwise movements, said spring being disposed to resist said sliding movements, and means to connect one casting to the throw rod and the other to the head rod.

95. 6. A spring head rod for split switches comprising one member connected to the switch, another member connected to the switch operating mechanism, said members being superimposed and recessed to jointly 100 form a spring housing, said members having end extensions, a pipe sleeve which receives and guides the extensions at the corresponding ends of the members, means to secure each sleeve to one member only, leaving the other member free to slide therein, and a coil spring in said housing adapted to resist said sliding movements of the members.

105. 7. A spring head rod for split switches comprising one member connected to the switch, another member connected to the switch operating mechanism, said members being superimposed and recessed to jointly 110 form a spring housing, said members hav-

ing end extensions, a pipe sleeve which receives and guides the extensions at the corresponding ends of the members, means to secure each sleeve to one member only, leaving the other member free to slide therein, a coil spring in said housing adapted to resist said sliding movements of the members, and stop lugs on the member connected to the switch operating mechanism adapted to limit said sliding movements.

8. The combination with a split switch head rod, of a spring housing member having a lateral flange bolted to the head rod, a second spring housing member superimposed on said flanged member and having

an end extension adapted for connection to a switch throw rod, guides to hold said members assembled free for lengthwise relative movements, a spring chamber formed partly in each member, a spring disposed 20 in said chamber and adapted to resist relative lengthwise movements of said members, and protecting flanges on the upper member adapted to cover the spring chamber in all relative positions of said members. 25

In testimony whereof I affix my signature.

ROBERT E. YOLTON.
